PIEZOELECTRIC TRANSDUCER

Harry B. Shapiro, Cleveland Heights, Ohio, assignee to The Brush Development Company, Cleveland, Ohio, a corporation of Ohio

Application June 27, 1942, Serial No. 448,818

15 Claims. (CL 179—110)

This invention relates to piezoelectric transducers and, more particularly, to microphones suitable for use in hearing-aid devices.

A portable hearing aid device of the general type to which this invention pertains is disclosed in the U. S. Patent to Wengel, No. 2,192,669. Such apparatus usually comprises a carrying case wherein are disposed one or more amplifier tubes and the electric batteries required for operation, one wall of the case being provided with an opening behind which is mounted a microphone. Resilient means are sometimes interposed between the microphone-housing and the wall of the carrying case, for the purpose of minimizing the transmission of noise vibrations from the case to the microphone-elements, by way of the microphone housing, but such means have not given entire satisfaction.

It is, accordingly, an object of this invention to provide a microphone that shall not require extraneous resilient supports.

Another object is to provide a microphone that shall be highly sensitive over a pre-determined frequency-range.

Another object is to provide a microphone the response characteristic of which includes a plurality of peaks distributed over the useful audio frequency range.

Another object is to provide a microphone that shall be particularly adapted for installation into a hearing aid device.

Another object is to provide a microphone that shall be substantially immune to noise vibrations.

Another object is to provide a microphone that may be mounted rigidly in the carrying case of a hearing aid device, without strong microphonic effects.

A still further object is to provide a microphone having improved low frequency response.

In the specific embodiment of the invention chosen for purposes of explanation, a piezoelectric crystal unit and an actuating diaphragm therefor are both affixed to and are carried by a "floating" element, having relatively high inertia, such as a metallic disc or the like. The disc is supported within a rigid, cup-shaped housing by flexible means, such as an annulus of rubber or the like, affixed to its periphery. Preferably, the stiffness of the suspension annulus is so correlated to the total mass of the mounting ring, crystal unit and diaphragm that the assembly has a natural period of vibration, with respect to the housing, at a low audio frequency. Electrical connection is made to the

crystal unit by way of two conductive rivets or the like which extend through an end wall of the housing and to the inner ends of which the leads from the unit, respectively, may be soldered or otherwise affixed. Inasmuch as the leads are protected against breakage they may be made from metal foil so thin, and having such slight stiffness with respect to the inertia of the ring, that they cannot function to transmit vibrations to the crystal unit from the housing.

The novel features considered characteristic of the invention are set forth with particularity in the appended claims. The invention itself, however, both as to its organization and method of operation, together with further objects and advantages thereof, will be understood best from the following description of a preferred embodiment, taken in connection with the accompanying drawings, in which:

20 Figure 1 is a conventionalized front view in elevation of a hearing aid device embodying the invention.

Figure 2 is a greatly enlarged, dimensionally exaggerated and conventionalized cross-sectional view of the device, taken along a line corresponding to the line II—II in Figure 1.

Figure 3 is an enlarged plan view of the mounting disc and the crystal unit affixed thereto.

Figure 4 is a greatly enlarged and dimensionally exaggerated sectional view exemplifying the manner in which the mounting ring may be supported from the microphone housing.

Figure 5 is a conventionalized curve exemplifying the improved low frequency response of a microphone constructed according to the invention, and

Figure 6 is a conventionalized circuit diagram illustrating the electrical analog of the improved microphone.

40 Figure 7 is a view somewhat like Figure 4, but showing a modification of the manner in which the mounting ring may be supported from the microphone housing.

Before passing to the detailed description of a specific embodiment of the invention, it is to be understood that the figures of the drawings are highly conventionalized for purpose of explanation and that no attempt has been made to illustrate a commercial embodiment of the invention, to scale.

In all figures of the drawings, identical elements are similarly designated.

Referring now to the drawings, a preferred embodiment of the invention comprises a massive mounting disc or ring 1 having appreciable in-

ertia, to one face of which is cemented the flexible periphery 2 of a stiff conical diaphragm 3 and to the opposite face of which are cemented or otherwise affixed three corners of a Rochelle salt crystal unit 5 of the twister type. The crystal unit may be a "Bimorph" such, for example, as is disclosed in United States Reissue Patent 20,680, but it is to be understood that the invention is not limited to units of any particular type.

In order that the disc shall have relatively large inertia, a metal such as brass is suitable therefor. However, any available material having high specific gravity and sufficient stiffness may be utilized.

The mounting ring 1 has a central opening 7 through which extends a drive link 8 that interconnects the apex of the diaphragm 3 with the free corner of the crystal unit 5. The central opening may be proportionately larger or smaller than illustrated, and the crystal unit may be mounted on the same side of the disc as the diaphragm, if desired.

A flexible suspension annulus 10 of rubber or of analogous material is cemented to the periphery of the mounting ring 1 and the outer edge of the annulus is held between the rim of a cup-shaped microphone case 11 and the matching rim of a cover-plate 13 having an opening 15 therethrough concentric with the diaphragm. The rim of the cup-shaped case and the rim of the cover-plate may be stepped, as shown in Figure 4, for the purpose of tightly gripping the periphery of the suspension annulus and the periphery of the annulus may be cemented thereto. It also lies within the scope of the invention to extend the flexible rim of the diaphragm itself beyond the edge of the mounting ring and to utilize the extension in lieu of the suspension annulus, as is shown in Fig. 7.

A plurality of conductive rivets 17 or the like extend through the bottom of the cup-shaped case 11, to the inner ends of which, respectively, the leads 19 from the crystal unit are electrically connected, as by soldering. Inasmuch as the leads are protected against mechanical injury by the case 11, they may be made from metal foil having a thickness of the order of .001 of an inch and, because of their extreme flexibility, they do not convey mechanical vibration from the case to the mounting ring or to the crystal unit and the diaphragm supported thereon.

A small opening 21 is provided through the bottom of the cup-shaped case 11, whereby changes in atmospheric pressure on the diaphragm are compensated.

In use, the improved microphone may be rigidly mounted within a carrying case 23, wherein are also disposed the necessary thermionic amplifying tube or tubes, batteries, volume control devices, etc., (not shown). The carrying case, of necessity, is more or less open to the atmosphere at those points where the shafts of control devices, etc., extend through the walls thereof, thus permitting sound pressure to reach the back of the microphone diaphragm. The summation of the various openings is indicated, generally, by the numeral 25.

In order that a clear understanding of the operation of the invention may be had, attention is directed to Figure 6, which is a diagrammatic view of an electrical network wherein the various components function electrically in a manner analogous to the mechanical and acoustic response of the microphone and carrying case 75

to sound forces. In the circuit diagram, inductance corresponds to mechanical mass, capacity to mechanical compliance, current to velocity, charge to displacement and alternating potential to alternating sound forces. The elements of the circuit are as follows:

1. L_1 is an inductance representing the mass of air moving in the large opening 15.

2. L_2 represents the mass of diaphragm 3 and link 9.

3. L_3 represents the mass of mounting ring 1.

4. L_4 represents the effective mass of crystal unit 5.

5. L_5 represents the mass of air moving through the lower small opening 21 in the bottom of microphone case 11.

6. L_6 represents the mass of air moving through opening 25 in the carrying case 23.

7. L_7 represents the mass of air moving through opening 7.

8. C_1 is a capacitance representing the compliance of the air between the outer surface of diaphragm 3 and cover-plate 13.

9. C_2 represents the compliance of rim 2 of diaphragm 3.

10. C_3 represents the compliance of diaphragm-mounting annulus 10.

11. C_4 represents the compliance of the air trapped in microphone housing 11, below the mounting ring.

12. C_5 represents the compliance of crystal unit 5.

13. C_6 represents the compliance of the air trapped in carrying case 23.

14. C_7 represents the compliance of the air trapped between diaphragm 3 and mounting ring 1.

The connection 27 exemplifies the fact that sound forces can reach the rear of the diaphragm by way of the openings 25 and 7.

From an inspection of the circuit diagram, it will be apparent that the system has a plurality of degrees of freedom. Each degree, because of the strong coupling factors between the elements of the circuit, gives rise to a peak of current through the capacitor C_8 , and corresponds to a peak in the sensitivity of the system. In the actual design of a microphone, by proper choice of the circuit constants, these response-peaks may be caused to lie rather closely together within the range of voice-frequencies, as indicated in Figure 5, thus enhancing the overall sensitivity and particularly the sensitivity at the low end of the audio range. The circuit constants, after determination thereof either by calculation or experiment, may be translated into mechanical masses, compliances and dimensions through utilization of conversion formulae well-known to those skilled in the art. Although no damping elements are illustrated, it is to be understood that they may be included at strategic points, so to speak, such as in series with the capacity C_4 by means of a material such as flannel or the like, or in series with M_1 by disposing a foraminous plate (not shown) over or within the voice opening 15. The plate could be made from sintered metallic particles, such as is disclosed in the copending application of A. L. W. Williams et al., Serial No. 429,896, now refiled as Ser. No. 541,694, or from any other material having analogous properties.

In the preferred embodiment I support the microphone case 11 within the carrying case 23 by suitable supporting means such as plastic cement, and so correlate the volume of the microphone case to the volume of the carrying case that

the sensitivity of the microphone is enhanced by resonance phenomena at a number of points within the range of audio frequencies, and particularly at a frequency on the order of 400 cycles per second.

A microphone constructed according to the invention has many advantages, among which may be mentioned the following:

1. The microphone may be rigidly mounted in a carrying case without being noisy.

2. The output from the microphone is not reduced provided the mounting ring has reasonably high inertia.

3. The low frequency response of the device is improved.

4. Mechanical vibrations are not transmitted to the crystal unit or diaphragm by the leads interconnecting the microphone with an accompanying amplifier.

Although a specific embodiment of the invention has been selected for purposes of explanation it is to be understood that many modifications are possible and it is not intended that such selection shall be construed as limiting the scope thereof. The invention, therefore, is not to be restricted except insofar as is necessitated by the prior art and by the spirit of the appended claims.

What is claimed is:

1. In combination, a cup-shaped microphone case having a substantially closed end, a rigid partition provided with a central opening, means for resiliently supporting the partition in the case substantially parallel to the end thereof, the supporting means also functioning to prevent air from flowing past the periphery of the partition upon movement thereof, a diaphragm resiliently affixed to said partition and sealing the opening therethrough, and a piezoelectric crystal unit mounted on said partition and operatively connected to said diaphragm for actuation thereby, the mass of the partition, the piezoelectric unit and the diaphragm forming with the resilient supporting means for the partition a system mechanically resonant to a low audio frequency.

2. In a hearing aid device, a carrying case defining substantially an enclosure and having at least one large and one small opening in a wall thereof, a microphone in a second case having at least one relatively large opening and one relatively small opening, and means for so supporting the microphone case within the carrying case that the said large openings substantially coincide, the said cases together constituting an acoustic low-pass filter with respect to sounds entering the carrying case by way of the small opening in the wall thereof.

3. The invention set forth in claim 2, characterized in this: that the said cases also function to enhance the response of the microphone, by resonance phenomena, at a plurality of points within the range of audio frequencies.

4. The invention set forth in claim 2, characterized in this: that the microphone is resiliently mounted within the microphone case.

5. The invention set forth in claim 2, characterized in this: that the microphone is resiliently supported within the microphone case, the supporting means being mechanically resonant to a low audio frequency.

6. In combination, a microphone unit case, a mounting device having appreciable inertia, means for resiliently supporting said device within said case for limited movement substantially axially thereof, a piezoelectric transducer

mounted on said device for movement therewith, and electrical connections having stiffness low compared to the stiffness of said resilient supporting device extending between said transducer and the wall of said case.

5 7. The invention set forth in claim 6, characterized in this: that the mounting device and the resilient supporting means therefor constitute a substantially closed partition.

10 8. In a hearing aid having a casing which when worn by a user is subject to mechanical noise vibrations, a microphone unit case rigidly mounted within said hearing aid casing and subject to the mechanical noise vibrations of the said hearing aid casing, mounting means within said microphone unit case, a diaphragm mounted on said mounting means and lying within said hearing aid casing, a piezoelectric transducer connected to said diaphragm and mounted on said mounting means, said piezoelectric transducer having an inertia small compared to the inertia of said mounting means, and resilient means supporting said mounting means from said microphone unit case whereby the transmission of mechanical noise vibration through said support from the microphone unit case to the diaphragm is minimal.

15 9. In a hearing aid as set forth in claim 8, the further characterization that the inertia of the said mounting means is large compared to the combined inertia of said piezoelectric crystal means and said diaphragm.

20 10. In a hearing aid as set forth in claim 8, the further characterization that the said resilient means comprises the annular edge portion of said diaphragm.

25 11. In a hearing aid as set forth in claim 8, the further characterization that the said piezoelectric transducer includes thin flexible lead means connected to the said microphone unit case, and that the stiffness of said lead means is small compared to the stiffness of the said resilient means whereby the transmission of mechanical noise vibrations through said lead means from the microphone unit casing to the piezoelectric crystal means is minimal.

30 12. In a hearing aid as set forth in claim 8, the further characterization of an opening through said mounting means into an enclosure defined by said mounting means and said diaphragm means, and of an opening through the wall of said microphone unit case, the said two openings and the cavity between the two housings and the space 35 between the mounting means and the microphone unit case establishing an acoustic resonant chamber.

35 13. In a hearing aid as set forth in claim 8, the further characterization that the said diaphragm and the said piezoelectric transducer are mounted on opposite sides of said mounting means and a coupling drive pin connects the piezoelectric transducer to said diaphragm through an opening in said mounting means, said opening being 40 an acoustic vent tuned to establish a resonance 45 within the frequency range of said hearing aid.

40 14. In a microphone adapted for installation within a housing for a hearing aid device by rigid connection thereto without introduction of excessive mechanical noise vibrations through said connection to said microphone, a microphone case adapted for rigid attachment to the hearing aid housing, a mounting device, resilient means supporting said mounting device within said case, and 45 a piezoelectric transducer mounted on said mount-

ing device for movement with respect thereto, the inertia of said mounting device being large compared to the inertia of the transducer, and the mass of the transducer and of the mounting device and the stiffness of said resilient means determining a system mechanically resonant to a low audio frequency.

15. In a microphone as set forth in claim 14, the further characterization of flexible leads extending from said piezoelectric transducer to terminals mounted on said microphone case, the stiffness of said leads being less than the stiffness of resilient means.

HARRY B. SHAPIRO.
